UNITED STATES PATENT OFFICE

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK

WINDOW AND WINDOW SASH CONSTRUCTION

Application filed June 4, 1929. Serial No. 368,315.

This invention relates to window sash constructions and to constructions which are particularly applicable for vehicles, as railway cars, motor busses and the like; and it has for its object window and sash constructions which are rigid, light and comparatively narrow in construction and highly efficient and durable in use.

The invention consists in the novel features and in the combinations and constructions hereinafter set forth and claimed.

In describing this invention, reference is had to the accompanying drawings in which like characters designate corresponding parts in all the views.

Figure 1 is a front elevation of a window sash embodying this invention.

Figure 2 is an enlarged fragmentary view, partly in section, of a corner portion of the window sash embodying my invention, the adjacent portion of the window guide being also shown.

Figure 3 is a fragmentary sectional view on the plane of line 3—3, Figure 2, the contiguous portion of the window frame of a car structure being shown in section.

Figure 4 is a transverse fragmentary sectional view through the sill of the window frame, the contiguous portions of the window guide and of the bottom rail of the sash being also shown.

Figure 5 is a sectional view along line 5—5, Figure 2.

Figure 6 is a detail sectional view of one of the corner brackets.

1 designates the sash. 2 designates the stiles or upright members; 3, 4 the bottom and top members or rails which are formed up of sheet metal so that said members are hollow.

The stiles and rails are formed in any suitable manner to provide a channel 5 which receives the margin of the pane 6, the margin of the pane being seated in a rubber channel 7 seating in the channel 5. One of the members or rails carries sash holder means and as the sash here shown is designed to be lowered into a well beneath the sill, the sash holder means is carried by the top rail 4.

The sash holder means comprises a sliding latch bolt 8 movable lengthwise of the top rail

4 and normally projecting beyond one edge of the sash to coact with a rack 9 supported in the window guide 10. The bolt 8 is spring pressed and is withdrawn against the action of the spring by operating means comprising a rocking lever mounted on one of the side walls of the top rail 4 and located entirely within the width of said rail, this lever having an arm connected to the bolt 8 and a hand engaging portion extending transversely of the axis of the lever, so that the lever is operated by a small twisting action of the hand and also so that the hand engaging portion provides a wide abutment for the hand for lifting the sash or for lowering the sash. It will be understood that there are two bolts and two operating levers located at each end of the top rail 4.

11 designates the lever which is mounted upon a stud 12 provided on a base plate 13 which is secured to the top rail 4. The arm 14 of the lever is formed with a pin or stud 15 extending through a slot 16 in the base plate and an aligned slot 17 in a wall of the rail 4, this pin 15 extending through a wall in the latch member 8. The slots 16 and 17 are slightly arcuate about the axis of the lever, and the arm 14 is flat and wide or in the form of a plate sufficiently broad to cover the slots 16 and 17 in all angular positions of the lever 11.

19 is the hand engaging portion, this projecting at an angle to the lever or at an angle to the plate 14 and extending on opposite sides of the axis of the lever and farther to one side than the other. This hand engaging portion extends comparatively near the axis and is also preferably arcuate. It is so located as to be conveniently twisted by the hand with the forefinger underlying and the thumb overlying the hand engaging portion 19.

As seen in Figure 5, the base plate 13 is secured to the top rail by means of the two screws at each end of the base plate, one screw 20 extending through the base plate and coacting with the other screw 21 extending from the other side of the top rail and one of the screws, as the screw 21 being a sleeve screw for receiving the other screw 100.

20. These screws extend into a tubular projection 22 on the base plate which extends transversely through the top rail, the projection 22 terminating close to the inner face of the wall of the top rail opposite to that wall on which the base plate is located. 5
The latch bolt 8 is here shown as guided in its movement by a corner iron or bracket 23 located at the upper corners of the sash. Similar corner irons but unprovided with 10 latch bolts may be provided at each lower corner of the sash. Each corner iron or bracket 23 is formed up of sheet metal to have legs 24 and 25 which seat within the top rail and the stiles, and these legs are 15 U-shaped in cross section with the bottom of the U-formation toward the edge of the top rail and the stile respectively. The bottom at the edge of the stile and near the corner is cut away to form an opening 26. 20
The leg 24 of the corner bracket is formed with an internal lug 27 formed with a passage 28 alined with the opening 26. The opening 26 is rectangular and the latch bolt 8 includes a portion rectangular in cross section which slides in the opening 26 and also with a round rod portion which slides in the opening 28. This rod portion is flattened at its inner end where it coacts with 25 the pin 15 of the operating mechanism. A spring 29 encircles the rod portion and thrusts at one end against the lug 27 and at its other end against a shoulder 30 at the inner end of the rectangular portion of 30 the latch bolt 8. A transverse pin or rivet 31 extends transversely through each leg 24 and the front and rear walls of the top rail 4 and this pin or rivet is so located as to form a guide or rest for the latch bolt 8. 35
32 designates the frame of a car structure at the upper end of the sash, this including spaced apart sheet metal plates 33 and 34 connected or bridged by a channel member 35 which receives the top rail. A weather strip 36 is provided on the outer face of one side of the flanges of the channel 35 to coact with the outer face of the top rail 4 when the sash is in its upper or closed position. 40
37 designates the car lining having its margin bent back to form a groove which receives the margins of the plate 34 and one of the side walls of the channel 35. 45
40 and 41 designate outer and inner opposing sections of the sill construction, these being spaced apart to form a slot 42 through which the sash slides. These sections are formed with overhanging portions 43, and 44 respectively, and the overhanging portion 43 is provided by the metal sheeting 45 of 50 the outer section 40. The sash guides 10 extend above the slot 42 and sash guides, as the guides 46 extend below the slot 42. The bottom rail 3 of the sash is formed with the weather strip 47 along its bottom edge which 55 coacts with said overhanging portions 43

and 44, the weather strip extending beyond the inner and outer faces of the bottom rail and having an upturned flange 48 at its outer edge extending between the outer face of the bottom rail 3 and the inner edge of the overhanging portion 43 of the outer section 40 of the sill so as to form a weathertight joint when the sash is closed. There is a depending window guide 46 at each side of the sash and each of these guides is in the form of a 70 channel for receiving the stiles 2 of the sash when the sash is open. 75

The sides of each channel 46 flare outwardly toward the upper ends to guide the sash therein. Each guide 46 is also provided with 80 one or more compression devices for pressing against the stiles and holding the sash from rattling when the sash is lowered below the sill. Each compression device, as here illustrated, comprises a shoe 50 extending through 85 a slot 51 in one side wall of each channel 46, the shoe having lugs 52 at its ends lapping the outer sides of the wall of the slot 51 and these lugs are provided with openings which slidably receive studs 53 secured at like ends in 90 one of the side walls of the channel 46 and at their other ends in an offset frame or brace strip 54 carried by one of the side walls of the channel 46. Compression springs 56 encircle the studs 53 and thrust against the ends 95 of the shoe 50 and against the offset portion of the strip 54.

The sash when closed, occupies the positions shown in Figures 3 and 4 with respect to the window frame. To lower the sash, the operator takes hold of the hand portions 100 19 of the levers 11 and twists said levers toward the outer edges of the sash, thus withdrawing the bolts 8 from the rack 9 and either lets the sash drop or lets it down gently into the wall or guides 46 below the sash. The compression device or shoe 50 prevents violent dropping of the sash. 105

To close the sash the operator may merely lift up on the levers 11 as usually no teeth 9 are provided in the racks 10 to lock the sash in wide open position. During the lifting operation, the bolts 8 will ratchet past the teeth of the rack, as between the ends of the bolts and the rack teeth are formed to permit 110 ratcheting action.

This sash construction is particularly advantageous in that it is particularly light and rigid and at the same time the sash members are narrow and also the sash holder operating 115 means, owing to its location and construction within the comparatively narrow width of the top rail of the sash.

What I claim is:

1. In a window sash construction, the combination of a hollow sash member, a latch bolt movable lengthwise of said member within the same and normally projecting beyond the edge of the outer side of the sash and an operating member mounted on the sash member 120

and comprising a pivoted lever having one arm connected to the latch bolt and its other arm provided with a hand engaging portion extending transversely of the axis of the lever and the former arm and extending to the opposite sides of the axis of the lever.

5 2. In a window sash construction, the combination of a hollow sash member, a latch bolt movable lengthwise of said member within the same and normally projecting beyond the edge of the sash, and an operating member mounted on the outer side of the sash member and comprising a pivoted lever having one arm connected to the latch bolt and its other arm provided with a hand engaging portion extending transversely of the former arm and the axis of the lever and on opposite sides of the axis of the lever, and extending farther on one side of the axis than on the other.

20 3. In a window sash construction, the combination of a hollow sash member, a latch bolt movable lengthwise of said member within the same and normally projecting beyond the edge of the sash, and an operating member mounted on the outer side of the sash member and comprising a pivoted lever having one arm connected to the latch bolt and its other arm provided with a hand engaging portion extending transversely of the former arm and the axis of the lever and extending on opposite sides of the axis of the lever, the hand engaging portion being arcuate.

25 4. In a window sash construction, the combination of a hollow sash member, a latch bolt movable lengthwise of said member within the same and normally projecting beyond the edge of the sash, an operating member mounted on the outer side of the sash member and comprising a pivoted lever having one arm connected to the latch bolt, and its other arm provided with a hand engaging portion extending transversely of the former arm and the axis of the lever and on opposite sides of the axis of the lever, the hand engaging portion being arcuate and projecting outwardly at an angle to the plane of the former arm and extending farther on one side of said axis than on the other.

30 5. In a window sash construction, the combination of a hollow sash member, a latch bolt located within the sash member and movable lengthwise thereof and normally projecting beyond one edge of the sash, and operating means mounted on the outside of the sash member and comprising a base plate having a slot, the sash member having a slot aligned with the former slot and a lever pivoted to the outer side of the base plate and having one arm of sufficient width to cover the slot in the base plate in all angular positions of the lever, said arm having a projection extending through the slots and connected to the latch bolt, the lever having a hand engaging portion.

6. In a window sash construction, the combination of a hollow sash member, a movable latch located in said member and normally projecting beyond one edge of the sash, and operating means for the latch comprising a base plate having a slot mounted on the outer side of the sash member, an operating lever pivoted on the base plate and a pin extending from the lever through the slot in the base plate into the interior of the sash member and coacting with the latch, the lever covering the slot at all times.

In testimony whereof, I have hereunto signed my name, at Syracuse, in the county of Onondaga, and State of New York, this 20th day of May, 1929.

CERTIFICATE OF CORRECTION.

Patent No. 1,885,216.

November 1, 1932.

ROY T. AXE.

It is hereby certified that error appears in the printed specification of the above numbered patent requiring correction as follows: Page 2, line 129, strike out the words "outer side of the" and insert the same before "sash" in line 130; and that the said Letters Patent should be read with this correction therein that the same may conform to the record of the case in the Patent Office.

Signed and sealed this 17th day of January, A. D. 1933.
